Attorney

UNITED STATES PATENT OFFICE.

THOMAS F. GORE, OF YONKERS, NEW YORK.

WRENCH.

Application filed November 13, 1919. Serial No. 338,999.

To all whom it may concern:

Be it known that I, THOMAS F. GORE, a citizen of the United States, residing at Yonkers, in the county of Westchester and State 5 of New York, have invented certain new and useful Improvements in Wrenches, of which the following is a specification.

This invention has relation to wrenches and more particularly to pipe wrenches; it 10 being the primary object of the present invention to provide a device of the character mentioned which will be efficient in operation and convenient to handle, owing to its light weight.

15 A further object is to provide a device including but a small number of parts, one of such parts comprising a movable jaw intended to normally remain in close proximity to a stationary jaw and adjustable away 20 from the stationary jaw to permit insertion of a pipe or other object thereunder.

With these and other objects in view, my invention consists in the arrangement, and combination of parts hereinafter more fully 25 described and pointed out in the accompanying drawings, in which—

Figure 1 is a side view of the improved wrench,

Figure 2 a bottom view, and

30 Figure 3 a vertical section taken on the line 3—3 of Figure 1 looking in the direction of the arrows.

The wrench handle 1 may be made to any size for handling and is preferably of a narrow width as will be noted from the lower edge 2, shown in the drawing. The handle preferably tapers toward the outer or gripping end 3 and has at its opposite end a stationary jaw 4, formed integral therewith, 35 but of a greater width, thereby providing a shoulder 5 on each side of the wrench handle. That portion of the handle immediately rearward of the stationary jaw 4 and to which the outer or movable jaw 6 is attached 40 is slightly enlarged or thickened by the outwardly curved edge portions 7 and 8 respectively so as to strengthen the wrench handle at this point, against the strain incident thereto during the using of the wrench. The 45 under face 2 of the wrench handle 1 is provided in proximity to the jaw 4 with a channel 9, in which is partially received a coiled spring 10, one end of which is fastened to a screw 11 carried by the wrench handle adjacent one end of the channel. The other end 50 of the coil spring 10 is hooked about a bolt

12 carried by the outer jaw 6. The channel 9 serves as a path and guide for the spring 10 preventing said spring from riding over either side of the handle when it is expanded 60 by movement of the jaw 6 and permits the spring to ride evenly over the arcuate edge 8 of the wrench handle.

The outer jaw 6 comprises a solid jaw portion 13 substantially larger than the inner 65 jaw 4 being projected an appreciable distance beyond the latter to provide an auxiliary or gripping portion 13' and provided with a concaved inner face upon which are formed teeth 14, adapted to engage a pipe or 70 other object inserted between the outer jaw 13 and the inner jaw 4. The shank 15 of the jaw 6 extends angularly away from the toothed face 14 and is bifurcated to provide arms 16 and 17 respectively which embrace 75 the wrench handle 1, rearwardly of the shoulder 5 of the inner jaw 4 and are pivotally supported upon a bearing pin 18. Connecting the arms 16 and 17 at their outer ends is the cross pin 12, previously referred to, and 80 to which is hooked one end of the coil spring 10.

The coil spring 10 is tensioned so as to draw upon the cross pin 12, moving the outer jaw 6 upon its pivot pin 18 and bringing the toothed face 14 in close proximity to the outer curved tooth bearing face 19 of the stationary jaw 4; such movement of said outer jaw being controlled or limited by reason of the cross pin 12 abutting against 90 the flanges of the channeled-portion of the under face 2 of the wrench handle, such abutment occurring after the pin has ridden over the hump portion 8, as indicated by the dotted lines of Figure 1, and thereby allowing the end of the coil spring 10 which is secured to the pin 12 to freely travel within the groove 9, whereby the wear of the coil spring against the inner face of the groove 9 is eliminated.

100 In operation, the pipe or other object to be gripped is inserted between the jaws of the wrench, the outer jaw 6 being moved about its pivot and expanding the spring 10 to widen the space between the respective 105 teeth bearing faces of the toothed jaws sufficiently to accommodate the pipe therebetween. Due to the retractive tendency of the spring the outer jaw 6 is always retained in close adherence to the pipe, etc. and forces it 110 up against the teeth of the inner jaw 4, so that upon movement of the wrench handle,

the teeth of the respective jaws are caused to bite into the pipe, etc., so that it is forced to turn with movement of the jaws. Whenever it becomes necessary to separate the 5 jaws to any considerable extent, as when the pipe or other object upon which the wrench is to be used, is of an unusually large circumference, such separation may be readily accomplished by placing the wrench up 10 against the pipe, etc., so that the teeth of the auxiliary gripping portion 13' of the outer jaw firmly engages the pipe, etc., and by using this portion as a fulcrum and bearing down upon the wrench handle until the jaw 15 4 is clamped against the object, the teeth of both jaws may be brought to bear against the object sufficiently for the purpose of turning it. The movement of the jaw 6 in separating from the inner jaw 4 is limited by 20 means of the cross pin 12 which abuts with the under edge 2 of the wrench handle, subsequent to its movement over the humped edge 8. It is thus seen that the pin 12 limits movement of the outer jaw either forwardly 25 or rearwardly of the inner jaw 4 and consequently its position between the arms 16 and 17 is a controlling factor in determining the extent of movement of the outer jaw, depending upon the proximity of its position 30 with respect to the outer extremity of the arms, or its nearness to the channeled face of the wrench handle.

Having thus described my invention what I desire to secure by Letters Patent is:—

- 35 1. A wrench comprising a handle having a serrated jaw and formed with a reenforced thickened body portion adjacent said jaw, a serrated jaw pivotally mounted centrally of said thickened body and provided with arms 40 straddling the sides of the handle, the ends

of said arms being normally disposed outwardly of the handle, a transverse pin secured between the arms, a resilient member fixed at one end to the pin and at its opposite end to the handle, said member lying 45 within a grooved guide in the handle and thickened body portion, when the jaws are moved to certain positions, said pin being adapted to ride over the said enlarged portion of the handle when the resilient member 50 is distorted and constituting a stop for the movable jaw in its open position.

2. A wrench comprising a handle having a serrated jaw, and formed with a reinforced thickened body portion adjacent said jaw, a serrated jaw pivotally mounted centrally of the said thickened body portion and provided with arms straddling the sides of the handle, the ends of said arms being normally disposed outwardly of the handle, 60 transverse pin secured between the arms, a resilient member fixed at one end to the pin and at its opposite end to the handle, said member lying within a grooved guide in the handle and the thickened body portion, said 65 pin adapted to engage the side edges of the groove for the purpose of allowing the ends of the spring connected thereto to freely travel within the said groove when the jaw is moved to its open position, said pin adapted to ride over the said enlarged portion of the handle when the resilient member is distorted and constituting a stop for the movable jaw in its open position.

In testimony whereof I affix my signature 75 in presence of two witnesses.

THOMAS F. GORE.
